APPARATUS FOR PILING SHEETS

William H. Mursch, Pittsburgh, Pa., assignor to
United States Steel Company, a corporation of
New Jersey

Application May 27, 1948, Serial No. 29,452

14 Claims. (Cl. 271—71)

1

This invention relates to the handling of sheet material and, in particular, to the piling of sheets, such as light-gauge metal sheets or the like, e. g., steel sheets, either tin-plate or tin-mill black plate.

Sheet steel is now largely produced by rolling strip and shearing it to length. If the material is tinned electrolytically in strip form, it is sheared for packing and shipment. Alternatively the uncoated strip is sheared and tinned as sheets by the hot-dip method. In either case, the speed of disposition of the sheared sheets in piles is one of the limiting factors on the speed of continuous strip manufacture. The speed of known sheet pilers is limited by the danger of injury to the sheet edges, particularly in the lighter gauges, by contact with stops and guides. This is caused by the momentum of the sheets resulting from their considerable mass compared to sheets of paper, for example. Bending of the sheet edges, furthermore, is not self-curing as in the case of paper.

I have invented a novel apparatus for piling, particularly adapted for metal sheets and capable of operating at a higher speed than the maximum obtainable by the aid of known pilers, without injury to the sheet edges. In a preferred embodiment, the sheets are discharged successively over a pile support and the tail end of each sheet is seized at the proper time to arrest it positively in vertical alignment with the support. The sheet is then released in mid-air and permitted to fall on the support. Thus the horizontal velocity of the sheet is reduced substantially to zero before it strikes a stop or starts to fall onto the support.

The apparatus of my invention includes a conveyor, delivery pinch rolls at the discharge end thereof and an electromagnetic suspension conveyor disposed over a pile support and cooperating with the pinch rolls. Clamping bars reciprocal between the pinch rolls and the suspension conveyor are actuated at the proper time to grip the tail end of a sheet as it passes from the pinch rolls to the conveyor and gradually decelerate it before releasing it. The travel of the bars is initiated by the sheets as they approach a position in vertical alignment with the support. All other operations in a single cycle are controlled automatically in accordance with the advance of the means actuating the clamping bars which is a crank and pitman effective to accelerate, decelerate and reverse the bars until the cycle is completed. These operations include de-energization of the magnets of the

2

suspension conveyor, closing of the bars to engage a sheet, deceleration of the suspension conveyor and opening of the bars as well as the momentary transfer of a source of compressed air from a pipe with upwardly directed nozzles for floating the sheet to a pipe with downwardly directed nozzles for forcing the tail end of the sheet downwardly toward the pile support. A pusher actuated by the clamps gently urges the sheets against a fixed end stop as they settle on the pile.

A complete understanding of the invention may be obtained from the following detailed description and explanation which refer to the accompanying drawings illustrating a present preferred embodiment. In the drawings,

Figure 1 is a plan view of the apparatus, certain portions being shown diagrammatically;

Figure 2 is a side elevation with parts omitted for clearness;

Figure 3 is a central longitudinal section taken along the line III—III of Figure 1;

Figure 4 is a partial transverse section taken along the line IV—IV of Figure 2 with parts in elevation; and

Figures 5 through 8 are diagrams showing the electrical control circuits for various elements of the apparatus.

Referring in detail to the drawings, the sheets to be piled are delivered by a conveyor 10 extending from a shear which serves to cut strip into the desired lengths. The conveyor 10 may be of any desired type and is, therefore, illustrated only diagrammatically. The conveyor delivers sheets successively between upper guide plates 11, 11^a and a lower guide plate 12 into the nip of a pair of pinch rolls 13 journaled in suitable bearings 14 mounted on a supporting base 15. The pinch rolls are geared together and are driven by any convenient source of power through a shaft 16, through a pinion 17 and a gear 17^a.

The pinch rolls deliver sheets between upper and lower transverse clamping bars 18 and 19 which are normally spaced apart into cooperating relation to a magnetic suspension conveyor 20. Air jets from a nozzle pipe 21 extending transversely beneath the clamping bars sustain the leading edge of the sheet until it comes within the field of influence of electromagnets 20^a of the conveyor 20. This conveyor, which is of known construction, also includes belts 20^b traveling around pulleys 20^c mounted on spaced shafts 22 and 22^a journaled in suitable bearings. The shaft 22 is driven from the shaft of one of

the pinch rolls 13 through a belt-and-pulley drive 23 and a magnetic clutch 24.

The upper clamp bar 18 constitutes a cross-head reciprocable on guide rails 25 mounted on any suitable supports. The lower bar 19 is suspended on the piston rods 26 of pneumatic cylinders 27 mounted at each end of the clamp 18. The bars are reciprocated between a position adjacent the pinch rolls 13 and a position adjacent the conveyor 20 by cranks 28 and pitmans 29. The cranks are mounted on a shaft 30 journaled above the discharge end of conveyor 10 in bearings 31. The shaft 30 is driven from shaft 16 through a magnetic clutch 32, a pinion 33 and a gear 33^a. The extension of shaft 16, designated 16^a, beyond the clutch 32 is provided with an electromagnetic brake 34 which becomes effective when energized to arrest the shaft. A pinion 35 loose on shaft 22 meshes with a rack 36 mounted on one end of the clamp 18. The clutch 24 has two windings adapted to be energized alternately. One causes the shaft 22 to be coupled to the shaft 23^a. The other causes the pinion 35 to be coupled to the shaft 22.

The operation of the clutches 24 and 32, brake 34 and cylinders 27 is controlled by switches operated by cams 37, 38, 39 and 40 mounted on the shaft 30. These cams are shown in the idle or starting position, with their switches and the circuits controlled thereby, in Figures 5 through 8. The shaft 30 is brought to rest, in a manner to be described later, by the brake 34, with the cranks 28 in the position shown in Figures 2 and 3, i. e., the bars 18 and 19 are normally retracted to their position adjacent the pinch rolls. Sheets approaching the pile on the conveyor 10 will ordinarily be quite close together. I accordingly drive the pinch rolls at a speed sufficient to accelerate each sheet as it is gripped thereby in order to provide separation between sheets.

As a sheet is delivered from the conveyor 10 between the guides 11, 11^a and 12, it is seized by the pinch rolls, accelerated and fed between the bars 18 and 19 and thence onto the conveyor 20 which advances the leading edge of the sheet over a pile-support 41. A control device, illustrated as a photo-electric cell 42 and a light source 43, is positioned as shown in Figures 2 and 3, to initiate a series of operations shortly before the leading edge of the sheet reaches an adjustable endstop 44. Instead of a photo-electric cell and light source, I may employ a trip switch or other equivalent control device. Figure 5 shows such a switch at 45. It will be understood, however, that if the photo-electric cell and light source are employed, they will serve, on interruption of the light beam, in the same manner as switch 45 to close the circuit controlled thereby.

Closing of switch 45 energizes a relay 46. Operation of the relay de-energizes the coil 34^a of brake 34 and energizes the coil 32^a of clutch 32. As a result, the brake 34 is released and shaft 16^a is coupled to shaft 16. Shaft 30 is thus driven to turn the cranks 28 and advance the bars 18 and 19. The cams 37 through 40 also rotate with the shaft 30. Cam 37 first operates a switch 47 which opens a back contact 47^a in the circuit of coil 34^a and closes a front contact 47^b which maintains energization of the coil 32^a, after switch 45 is opened.

After rotation of the shaft 30 through a predetermined angle, say 70°, cam 40 actuates a switch 48 which opens the circuit of a relay 49 controlling the energization of the magnets 20^a of conveyor 20. Because of the high inductance

of the magnet coils, the flux through their cores does not collapse immediately but only after the lapse of a predetermined time. The magnets, therefore, continue to attract the sheet into contact with the conveyor belts 20^b for a short time after operation of relay 49.

When the shaft 30 has turned through about 90°, at which time the bars 18 and 19 are advancing at maximum speed, the cam 38 operates its switch 50. The pinch-roll drive is so arranged that the maximum speed of the clamps will be substantially equal to the speed at which the sheet is fed to the conveyor 20 by the pinch rolls. When switch 50 is operated, it de-energizes the coil 24^a of clutch 24 which couples shaft 23^a to shaft 22. The operation of the switch also energizes coil 24^b of the clutch which couples pinion 35 to shaft 22. At the same time, the switch 50 energizes the operating coil 51 of a valve 52. The valve 52 when operated by coil 51 admits air under pressure to the cylinders 27 which immediately causes the lower clamp 19 to move upwardly, thereby gripping the sheet between it and clamp 18.

At this stage the leading edge of the sheet has traveled about half the distance between the point of interruption of the light beam from source 43 to photo-electric cell 42 (or the point of operation of switch 45) and the endstop 44. The magnets of conveyor 20 have been de-energized, the belts of the conveyor have been coupled to the reciprocating bars and the bars have been actuated to grip the sheet. On continued rotation of shaft 30, which remains coupled to shaft 16 through clutch 32, the bars are decelerated as they approach their extreme position adjacent the conveyor. The sheet and conveyor belts are thus simultaneously decelerated and finally arrested as the leading edge of the sheet engages the endstop 44. When finally released by the conveyor magnets, the sheet starts to fall by gravity onto the pile on support 41 between side guides 41^a. At this instant, i. e., after rotation of shaft 30 through 180°, cam 38 operates switch 50 back to its normal position, as shown in Figure 6. The coil 51 is deenergized, whereupon, the valve 52 returns to normal position permitting the exhaust of air from the cylinders 27. The lower bar 19 thereupon falls, releasing the sheet. At the same time, clutch coil 24^b is de-energized and coil 24^a is re-energized. This re-establishes the connection between the driving shaft 22 for the conveyor belts and the shaft 23^a.

Continued rotation of the shaft 30 retracts the bars 18 and 19. After rotation of the shaft 30 through about 300°, cam 39 operates its switch 53 to energize a valve coil 54. This coil operates a valve 55 to change the connection of a source of compressed air from the nozzle pipe 21 to a nozzle pipe 56 disposed above the path of the sheets adjacent the conveyor 20 and having its nozzles directed downwardly. The jets from pipe 21 are thus cut off and jets are discharged by pipe 56 to urge the falling sheet downwardly so that its trailing edge will clear the leading edge of the next succeeding sheet. The fall of the sheet permits re-establishment of the beam from the source 43 to the photo-electric cell 42 or opening of switch 45. This de-energizes relay 46 but the operation of its contact does not have any immediate effect. When the shaft 30 has turned through about 350°, however, it operates switch 47, de-energizing clutch coil 32^a and re-energizing brake coil 34^a. Operation of the brake arrests the shaft 30 sub-

stantially in the zero or starting position in which it is shown in Figures 2 and 3. As the shaft is arrested, cam 38 operates its switch 53 to transfer the connection from the source of compressed air from nozzle pipe 56 back to pipe 58. All the parts of the apparatus are thus restored to their original positions so that they are ready for the start of the next cycle of operations when the leading edge of the succeeding sheet reaches the position where it interrupts the beam from the source 43 to the photo-electric cell 42 or closes switch 45.

Since the sheets are arrested in accurately determined position over the pile support, they should fall on the latter with their edges in alignment. In order to insure exact alignment of the leading and trailing edges, however, I employ pusher fingers 57 extending upwardly from a shaft 58 journaled in suitable bearings. The shaft is rotated clockwise through a slight angle 20 by an engagement of the bar 19 with a finger 59 at one end of the shaft and is returned by a spring 60 when the clamp is retracted.

It will be apparent that the invention is characterized by numerous advantages over sheet pilers as known heretofore. In the first place, the piler of my invention may be operated at a higher speed than pilers which rely on fixed stops to arrest the sheets and avoids the possibility of injury resulting from the momentum of the sheets. The arrest of the sheets in a position above the pile support is effected by seizure of the tail and through the medium of traveling clamping bars which decelerate gradually to rest. The sheet is held above the pile support by the conveyor until it is in proper position to fall accurately on the pile. The bars engage the sheet when traveling at the same speed as the latter and the conveyor is decelerated along with the bars, thus avoiding any buckling of the sheets.

The controls for the various elements are simple cam switches which can readily be changed for accurate timing in order to insure that the desired sequence of operations will occur in proper order. The sequence, furthermore, is automatically controlled when once initiated by the arrival of a sheet at the proper position for deceleration. Up to that time, the sheet travels at maximum speed. The crankshaft actuating the clamping bars is automatically stopped at the correct position for the start of the succeeding cycle. The upwardly directed air jets sustain the leading edge of the sheet until it is within the effective range of the conveyor magnets and the downwardly directed jets blow each sheet out of the way of the next succeeding sheet.

Although I have illustrated and described only a preferred embodiment and practice of the invention, it will be recognized that changes may be made in the construction and procedure disclosed herein without departing from the spirit of the invention or the scope of the appended claims.

I claim:

1. Apparatus for piling sheets comprising means for discharging sheets toward a pile support, an electromagnetic suspension conveyor above said support adapted to receive sheets from said means, clamping bars reciprocable between said first-mentioned means and said support, and means establishing a temporary driving connection between said bars and said conveyor as a sheet approaches a position overlying said support.

2. The apparatus defined by claim 1 charac-

terized by said conveyor having a shaft and said last-mentioned means including a pinion loose on said shaft, a rack mounted to move with said bars and meshing with said pinion, and a clutch effective to connect said pinion to said shaft.

3. Apparatus for piling sheets comprising means for discharging sheets toward a pile support, an electromagnetic suspension conveyor above said support adapted to receive sheets from said means, clamping bars reciprocable between said first-mentioned means and said support, a drive for said conveyor and means effective to disconnect the conveyor from said drive and establish a temporary driving connection between said bars and said conveyor as a sheet approaches a position overlying said support.

4. The apparatus defined by claim 3 characterized by a member driven by movement of the bars, said last-mentioned means including a clutch selectively engageable with said drive or said member.

5. Apparatus for piling sheets comprising a pair of pinch rolls adapted to discharge sheets successively onto a pile support, a pair of co-operating clamping bars reciprocable sidewise between a position adjacent the rolls and a position adjacent the support, means set in operation by the arrival of the leading edge of a sheet from the pinch rolls at a predetermined point over said support for reciprocating the bars from the first-named position to the second and back, and pneumatic cylinders on one of said bars effective to cause them to close on a sheet passing therebetween.

6. Apparatus for piling sheets comprising a pair of pinch rolls adapted to discharge sheets successively onto a pile support, a pair of co-operating clamping bars extending transversely of the path of the sheets and reciprocable between a position adjacent the rolls and a position adjacent the support, means set in operation by the arrival of the leading edge of a sheet from the pinch rolls at a predetermined point over said support for reciprocating the bars from the first-named position to the second and back, and means for causing said bars to grip a sheet passing therebetween at a predetermined point in its travel.

7. The apparatus defined by claim 6 characterized by said first-mentioned means including a crank and pitman actuating said bars and an electromagnetic clutch effective to connect said crank to a power source.

8. Apparatus for piling sheets comprising means for discharging sheets toward a pile support, a pair of sheet-gripping bars extending across the path of the sheets and movable back and forth between said means and said support, means for reciprocating the bars toward and from said support and means for actuating the bars to grip a sheet passing therebetween as they approach the support.

9. The apparatus defined by claim 8 characterized by said reciprocating means including a crank and pitman and control means therefor actuated by the leading edge of the sheet.

10. Apparatus for piling sheets comprising means for discharging sheets toward a pile support, an electromagnetic suspension conveyor above said support adapted to receive sheets from said means, two nozzle pipes between said first-mentioned means and said conveyor, one pipe below the path of the sheet discharging upward jets and the other above said path discharging

downward jets, a change-over valve for transferring an air supply from the first pipe to the second and means for operating said valve as a sheet approaches a position over said support.

11. Apparatus for piling sheets comprising means for discharging sheets toward a pile support, transverse sheet-gripping bars reciprocable sidewise between said means and said support in the direction of the travel of the sheets, means for reciprocating the bars sidewise from said means toward said support and back and means for actuating the bars to grip a sheet passing therebetween as they approach the support, said last-mentioned means including control means driven by said second-mentioned means.

12. Apparatus for piling sheets comprising means for discharging sheets toward a pile support, transverse sheet-gripping bars reciprocable sidewise between said means and said support in the direction of travel of the sheets, means for reciprocating the bars sidewise from said means toward said support and back and means for actuating the bars to grip a sheet passing therebetween as they approach the support, said first-mentioned means being a pair of pinch rolls, a shaft for driving said pinch rolls, a clutch for connecting said second-mentioned means to said shaft, and means actuated by the sheets delivered by the pinch rolls for controlling said clutch.

13. Apparatus for piling sheets comprising a pair of pinch rolls adapted to discharge sheets successively onto a pile support, a pair of co-operating clamping bars parallel to said rolls reciprocable between a position adjacent said

rolls and a position adjacent said support, means for reciprocating said bars between said positions at a rate such that the maximum speed of the bars approaches that of the sheets, and means causing the bars to grip a sheet passing therebetween while the bars are traveling at a speed approximating that of the sheet, whereby the slowing down of the bars before reversal decelerates the sheet.

14. The apparatus defined by claim 13 characterized by said first-mentioned means including a crank and pitman arranged to accelerate said bars gradually and then decelerate them gradually.
